UNITED STATES PATENT OFFICE.

WILLIAM M. DUNCAN, OF ALTON, ILLINOIS.

FURNACE.

1,316,880.

Specification of Letters Patent. Patented Sept. 23, 1919.

Application filed November 20, 1915. Serial No. 62,508.

To all whom it may concern:

Be it known that I, WILLIAM M. DUNCAN, a citizen of the United States of America, residing at Alton, in the county of Madison, 5 State of Illinois, have invented certain new and useful Improvements in Furnaces, of which the following is a full, clear, and exact description, reference being had to the accompanying drawings, forming a part of 10 the specification.

My invention relates to a furnace equipped with a mechanical stoker and other elements adapted to be associated therewith to provide for the combustion of anthracite coal 15 on a traveling chain grate.

In the prior structures the coal receptacle is usually located at the front of the furnace and at a point outside of the fire box, and the chain grate traveling under the coal 20 receptacle, carries the fuel toward the rear of the furnace. These earlier structures usually include an ignition arch for transmitting the heat by radiation to the green coal, and the hot gases flow rearwardly, 25 away from the green coal. My improved anthracite burner differs essentially from the prior structures referred to, and owing to this difference the new structure is well adapted for use in burning anthracite coal.

30 In the preferred form of the invention, the coal receptacle is located within the fire box at a point above the rear portion of the traveling chain grate. The grate passes under the coal receptacle at the rear of the furnace 35 and carries the fuel toward the front of the furnace, the parts being so arranged that the hot gases passing from the fuel are directed backwardly with respect to the movement of the grate. The coal receptacle is thus located at a point where it will 40 be subjected directly to the heat of said gases. By constructing and arranging the parts in this manner the coal may be placed in an incandescent state before it reaches the traveling chain grate, and it will, therefore, ignite before or immediately after leaving the 45 receptacle. Since the hot gases are directed backwardly, toward the coal receptacle the coal will burn very readily after leaving the 50 coal receptacle.

With the foregoing and other objects in

view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims 65 hereunto appended.

Figure I is a longitudinal section of a furnace embodying the features of my invention.

Fig. II is a top or plan view illustrating 70 the endless fuel carriers and the draft box associated therewith, some of the fuel carriers being omitted.

Fig. III is a vertical section taken approximately on the line III—III, Fig. I. 75

Fig. IV is a detail view of the means for operating the gate, or barrier, at the front of the furnace.

1 designates the side walls of a furnace, and 2 designates tracks located between said 80 side walls. Side frames 3 and 4 are provided with wheels which rest upon the tracks 2. A drive shaft 5 mounted in the side frames at the front of the grate is provided with a series of sprocket wheels 6 which lie 85 between the side frames 3 and 4. An idle shaft 7 at the rear of the grate, is provided with idle wheels 8. The wheels 6 and 8 constitute supporting elements for a series of traveling fuel carriers, and each of these 90 fuel carriers comprises an endless sprocket chain 9 fitted to one of the sprocket wheels 6 at the front of the grate and also fitted to an idle wheel 8 at the rear of the grate. Each fuel supporting member is a rectangular 95 plate 10 having perforations for the admission of air to the fuel and provided with legs, the ends of said legs being secured to the pivot pins forming part of the endless chain structure.

To prevent undue leakage of air fuel, the fuel supporting members 10 lap each other as shown in Figs. I and III.

I will now describe the means for controlling the flow of air to different parts of the 105 fuel bed. Manifolds 12, 13 and 14, arranged transversely of the chain grate structure, are secured at their ends to the side frames 3 and 4. Air conducting pipes 15, passing through a furnace wall 1, are fitted to the 110 manifolds and provided with valves 16 for regulating the flow of air through the mani-

folds. Each valve 16 is adapted to control the draft in only one of the manifolds, and these valves may be adjusted independently of each other to vary the draft at different parts of the fuel bed. Any suitable blower, or blast device, may be used for forcing air through the air conducting pipes 15.

The draft boxes for conducting air from the manifolds to the fuel bed, are arranged 10 longitudinally of the grate, and each manifold is in communication with a series of the draft boxes. The manifold 12, near the front of the grate, communicates with draft boxes 17 and 17', the boxes 17' being located 15 at the sides of the grate, as shown in Figs. II and III, and the draft boxes 17 being located between said draft boxes 17'. Each of the draft boxes 17 and 17' is closed at its sides and ends, and open at the top to permit 20 the air to circulate through the perforations in the fuel supporting members 10. The different draft boxes are separated from each other to provide passageways for the endless sprocket chains 9 which travel between said 25 draft boxes.

Intermediate draft boxes 18 and 18', similar to the draft boxes 17 and 17', are provided with end walls 19 and bottom and side walls connecting said end walls. All of these 30 intermediate draft boxes 18 and 18' are in communication with the manifold 13, and they are separated from each other to permit the sprocket chains to pass between them. Rear draft boxes 20 and 20' are provided 35 with end walls 21 connected by side and bottom walls, said rear draft boxes being in communication with the rear manifold 14.

The front, intermediate and rear draft boxes are connected together to form several 40 longitudinal rows of draft boxes, but the draft boxes 17-17', near the front of the grate, are not in communication with the intermediate or rear draft boxes, and the intermediate draft boxes 18-18' are not in 45 communication with any of the other draft boxes. The air passing through the manifold 12 is forced through the fuel supporting members and into the fuel bed at points immediately above the draft 50 boxes 17-17', the air forced through the manifold 13, passes through the intermediate draft boxes and into the fuel bed above said boxes; and the air forced through the rear manifold 14 passes upwardly from the rear draft boxes 20 and 20' 55 at points between their end walls 21. It will be observed that the draft boxes are arranged to form three draft zones,—one near the front of the grate, one at the middle portion 60 of the grate and one at the rear. The draft in any one of these zones may be regulated by adjusting one of the valves 16, and the draft in any one zone may be varied without changing the draft in any other zone. Although the draft is preferably

created by forcing air through all of the manifolds 12, 13 and 14, it is to be understood that very satisfactory results may be obtained by drawing air downwardly from the rear draft boxes and through the 70 manifold 14, thereby creating an induced draft at points immediately above the rear portion of the grate.

22 designates tracks arranged in the upper portions of the draft boxes to receive the 75 lapped marginal portions of the fuel supporting members 10. Guide members 23, extending forwardly from the front ends of the draft boxes 17, are adapted to guide the fuel supporting members as they move forwardly from the draft boxes.

Discharge openings 24 are formed in the bottom of each draft box, said discharge openings being normally closed by doors or closures 25. The closures 25 in each row of 85 draft boxes are secured together by a connecting bar 26, so that all of the closures may be operated at the same time. The means for operating the closures comprises a rock shaft 27 having a series of arms 28, 90 the upper ends of said arms being secured to the closures 25 near the front of the grate. The means for actuating the rock shaft 27 comprises an arm 29 secured to one end of 95 said rock shaft, and an operating rod 30 connected to said arm. When the grate is in service, ash, etc., will drop through the perforations in the fuel supporting members and fall onto the bottom walls of the draft boxes. Such material may be removed by 100 opening all of the closures 25 when the air under pressure is flowing into the draft boxes. When these closures are open, the air will escape freely through the discharge 105 openings 24, thereby blowing the ash, etc., through said openings and onto the lower course of fuel supporting members. This material will be conducted rearwardly by the fuel supporting members and discharged 110 therefrom at points near the rear of the 110 grate.

In the preferred form of the invention, a coal receptacle 31 (Fig. I) is located in the fire box at a point immediately above the rear portion of the traveling grate. This coal receptacle is open at the top to receive the coal, and open at the bottom to permit the discharge of coal onto the grate. 32 designates water tubes extending across the 115 furnace at points adjacent the coal receptacle 31. A second coal receptacle 31' (Fig. I) is located outside of the fire box in a plane above the coal receptacle 31, and provided with a discharge opening 31''. The means for feeding coal from the coal receptacle 31', 120 comprises a pusher, or plunger 33, arranged in the lower portion of said coal receptacle at a point opposite the discharge opening 31''. 34 designates a guide rod secured to the pusher 33 and connected to a crank 35 125 130

by means of a pitman 36. The crank 35 is driven through the medium of a sprocket wheel 37, and a sprocket chain 38 passing over said sprocket wheel 37 and fitted to a sprocket wheel 39, the latter being fixed to one end of the drive shaft 5. The power mechanism includes a worm wheel 40 fixed to the drive shaft 5 (Fig. II) a worm 41 fitted to said worm wheel 40, and a power shaft 42 fixed to said worm. The pusher 33, in the coal receptacle 31 moves in unison with the endless chain grate, and a predetermined quantity of fuel is pushed through the discharge opening 31" at regular intervals, the driving mechanism being so constructed and arranged that any change in the rate of travel of the chain grate will result in a corresponding variation in the speed of the reciprocating pusher 33.

20 The arrows shown in full lines Figure I indicate the direction of movement of the coal, and the arrows shown by dotted lines indicate the direction of flow of the hot gases. The coal discharged from the local receptacle 31' drops into the receptacle 31, and it may be permitted to accumulate therein as indicated by dotted lines. It will be noted that the coal passing from the bottom of receptacle 31 is carried 25 forwardly by the traveling chain grate, and that the hot gases travel backwardly with respect to the movement of the coal. The coal receptacle 31 and the coal contained therein, is, therefore, subjected directly to the heat of the gases. The coal becomes very hot before it reaches the traveling chain grate and it may be ignited at the lower portion of the coal receptacle 31, or at 30 a point immediately in front of said receptacle. After passing from the coal receptacle, the ignited coal is subjected to the heat of the gases flowing backwardly from the front of the furnace so that it will burn freely in passing from one end of the furnace to the other. The fuel bed is also subjected to the action of the forced draft passing through the manifolds 12 and 13, and the coal in the receptacle 31 is subjected to the action of the draft passing through 35 manifold 14 and draft boxes 20-20' which lie directly below said coal receptacle. The draft passes through the coal receptacle 31, and the body of the coal contained therein is heated throughout by the hot gases passing upwardly from the grate if a forced draft is created at this point, or downwardly from the top of the coal receptacle if an induced draft is created in the manifold 14. I preferably force the air upwardly from 40 the bottom of the coal receptacle so that the body of the coal will be subjected to the heat passing from the ignited, or incandescent coal at the bottom of said receptacle. By constructing and arranging the parts substantially as herein shown and described, the

apparatus will serve as a highly efficient means for burning anthracite coal on a traveling chain grate.

Kindling material, such as paper, wood and bituminous coal, or the like, is placed 70 in the coal receptacle 31, and ignited before the apparatus is placed in service. A draft may be created in the coal hopper at this time by forcing air through the manifold 14. Thereafter, the mechanism may be 75 placed in motion to feed the burning fuel away from the coal receptacle, and since the direction of the draft is backwardly with respect to the movement of the fuel, the combustion of the fuel near the coal receptacle is at all times aided by the more 80 completely ignited fuel. The draft in the different manifolds may be regulated to suit the abnormal conditions in starting the fire. The ash is discharged from the grate 85 at the front of the furnace, and the thickness of the bed of ash at this point may be varied by adjusting a vertical movable gate or barrier 50. 51 designates sprocket chains secured to the gate or carrier 50, and also 90 secured to sprocket wheels 52, the latter being fixed to a shaft 53. An operating handle 54 (Figure IV) secured to shaft 53, may be adjusted to raise and lower the gate or barrier 50, and after such adjustment the 95 parts may be locked by a pawl 55 fitted to a ratchet wheel 56.

The combination of draft boxes and fuel carriers, arranged as herein disclosed, is claimed in an application for patent filed by 100 me November 20, 1915, Serial No. 62,507, furnaces, renewed May 8, 1919, Serial No. 295,699.

I claim:—

1. In a furnace, a traveling grate within 105 the furnace fire-box, a coal receptacle located in said fire-box immediately above said grate, said coal receptacle having an open bottom permitting coal therein to be supported by the grate while confined within a 110 given area above the grate, and means for delivering hot gases to the coal in said receptacle to heat it before it passes to the grate.

2. In a furnace, a traveling grate within 115 the furnace fire-box, a coal receptacle located in said fire-box immediately above said grate, said coal receptacle having an open bottom permitting coal therein to be supported by the grate while confined within a 120 given area above the grate, and means for delivering hot gases into contact with the exterior of said receptacle and the coal within said receptacle, thereby providing for thorough heating of the coal prior to its delivery from the receptacle to the grate.

3. In a furnace, a traveling grate within the furnace fire-box, a coal receptacle located in said fire-box immediately above said grate, said coal receptacle having an open 130

bottom permitting coal therein to be supported by the grate while confined within a given area above the grate, and means for conducting hot gases to said receptacle in a direction contrary to the direction of movement of said traveling grate.

4. In a furnace, a traveling grate confined within the fire-box of the furnace, a coal receptacle confined within the furnace fire-box immediately above said grate, said coal receptacle having an open top to receive a

supply of coal and an open bottom through which coal is delivered directly onto said grate, said receptacle serving to hold a supply of coal in contact with the grate for delivery thereto, and means for delivering hot gases to the coal in said receptacle, whereby such coal is thoroughly heated before it passes from the receptacle to the grate. 15

WILLIAM M. DUNCAN.
